FRANK McM. SAWYER, OF HIGHLAND PARK, TEXAS.

WALL CONSTRUCTION.

1,280,864.

Specification of Letters Patent. Patented Oct. 8, 1918.

Application filed January 30, 1917. Serial No. 145,441.

To all whom it may concern:

Be it known that I, FRANK McM. SAWYER, citizen of the United States, residing at Highland Park, in the county of Dallas 5 and State of Texas, have invented certain new and useful Improvements in Wall Constructions, of which the following is a specification.

This invention has particular relation to 10 that type of wall construction wherein plastic slabs are superimposed and secured together by concealed mortar joints.

The chief aim of the invention is to form 15 a wall of superimposed slabs having their four edges so shaped that when the slabs are set up, intercommunicating as well as intersecting mortar channels or ducts are formed between the slabs. These channels will extend both horizontally and vertically and 20 the construction contemplated is such that the channels will be completely concealed.

It is also proposed to construct a wall of 25 two sides or tiers spaced apart and connected at intervals by web plates and suitable ties.

In carrying out the invention slabs are 30 molded of plastic material and each is surrounded by a groove or channel in its four edges; thus when the slabs are superimposed in a wall intersecting and intercommunicating horizontal and vertical ducts are 35 formed by the registration of the grooves of one slab with those of the adjacent slabs. The edges of the slabs being in contact the ducts will be concealed. Fluid plastic material such as a concrete mixture can be 40 poured into the vertical ducts from the top of the wall and will flow down the vertical ducts and laterally into the horizontal ducts. This mixture when set will form a bond or 45 lock, whereby the slabs will be secured against lateral displacement. Further the joints will be finished and will not require any trowel or pointing up work. Reinforcing rods may be placed in the ducts.

In forming a double or two sided wall, 50 cross connecting webs and tie rods are employed. The webs are shaped to form hollow studs into which the fluid mixture may be poured. Metal clips for holding the parts in place are also used.

The construction of the webs and the reinforcing means is very important. Web plates are disposed vertically and transversely of the wall in break-joint relation. 55 Each plate is dished or channeled so that

when placed together a vertical duct is formed. A plastic mixture may be poured into this duct and a solid stud produced. The tie rods pass through the stud and the metal clips and assist in registering the 60 slabs and holding the vertically reinforcing rods against lateral displacement owing to the tension of the tie rods or wires.

The invention will be more readily understood from a perusal of the following specification and by reference to the accompanying drawings, wherein:

Figure 1 is an isometric view of a wall embodying the invention,

Fig. 2 is a detail plan view,

Fig. 3 is a transverse vertical sectional view on the line 3—3 of Fig. 2,

Fig. 4 is a transverse vertical sectional view through one of the sides of the wall, and

Fig. 5 is a perspective detail of the metal clip.

In the drawings the numeral 1 designates a flat rectangular slab molded of plastic material as desired. Each slab has channels or grooves 2 in its upper and lower edges and similar channels or grooves 3 in its ends, whereby each slab is completely surrounded by a continuous channel or groove. When the slabs are assembled in a wall the grooves of one slab will register with those of the adjacent or contacting slabs so that vertical and horizontal ducts will be formed. The grooves may be given different cross-sectional shapes or contours and the resulting ducts may thus be formed to exhibit in cross-section, either a circular shape as shown or some other form. The grooves are formed entirely within the edges of the slabs, marginal surfaces of the edges being retained and coming into contact when the slabs are assembled. It is obvious that the ducts will be concealed.

Each slab has a shouldered vertical recess 4 at each end for receiving a vertical tongue 5 on the end of a transverse web plate 6. In all cases horizontal and vertical reinforcing rods 7 and 8, respectively are placed in the ducts. When the wall is built to the desired height or at intervals during 105 the building, fluid plastic material is poured into the vertical ducts. This material or mixture flows down the ducts and laterally into the horizontal ducts and forms an integral bond whereby the slabs are locked 110

against lateral displacement as well as vertical displacement. The contacting edges of the slabs are made to fit so nicely that no trowel or finishing work is required, therefore cheap labor can be employed.

The web plates are constructed with a recessed or wide channel portion 9 in one side, said portions registering when the plates are set up in contacting relation. The 10 plates are superimposed in break-joint relation as shown in Fig. 3. The tongues fitting in the recesses 4 hold the plates against lateral displacement when fluid plastic material is poured into the vertical ducts formed by 15 the portions 9. Tie wires 10 are passed between the plates and tied to the rods 7 and 8 at the intersections of the latter, this not only tying the intersections of the rods together, but tending to bring the slabs into 20 close contact with the ends of the plates. At each intersection of the rods and the wires, an angular metal clip 11 straddles the tie wires and has divergent legs 12 bearing against the shouldered portions of the slabs. 25 The clips are disposed in the vertical ducts so that their vertical ridges bear against the vertical rods 8 and hold the same in the center of the ducts.

It will be clearly seen that the completed 30 wall presents a reinforced structure of a very substantial and inexpensive nature.

The foregoing description and illustration clearly express the invention, but it is to be understood that said illustration is merely

an exemplification and the invention may be 35 carried out in various other ways.

What I claim, is:

1. A wall construction formed of two sides of slabs in which reinforcing rods are concealed and connected by web plates in 40 which tie wires are embedded, said tie wires being tied to the reinforcing rods, in combination with metal clips mounted on the wires and rods at the intersection of the same and within the sides of the wall, said 45 clips holding the rods in position against the transverse strain of the tie wires.

2. In a wall construction, two upright spaced sides composed of vertical slabs, vertical and horizontal ducts formed in the 50 abutting edges of the slabs of each side, horizontal and vertical reinforcing rods disposed in said ducts, cement cores surrounding the rods between the slabs, each slab having a shouldered recess at its end, transverse upright web plates having reduced shouldered ends and recessed sides, the web plates being disposed with their recesses in registration and their reduced ends embedded in the end recesses of the slabs, the 55 registering recesses of the plates constituting vertical ducts for receiving a plastic material, cross wires extending from the intersections of the rods in one side through the recesses of the plates to the intersections of 60 the rods in the other side.

FRANK McM. SAWYER.
